US00D939185S

(12) **United States Design Patent** (10) Patent No.: **US D939,185 S**
Bindra et al. (45) Date of Patent: **** Dec. 28, 2021**

(54) **CONFECTION**(71) Applicant: **Intercontinental Great Brands LLC**,
East Hanover, NJ (US)(72) Inventors: **Mandeep Bindra**, East Hanover, NJ
(US); **William Hirt**, East Hanover, NJ
(US); **Shelley Markoulis**, East
Hanover, NJ (US)(73) Assignee: **INTERCONTINENTAL GREAT
BRANDS LLC**, East Hanover, NJ (US)(***) Term: **15 Years**(21) Appl. No.: **29/773,394**(22) Filed: **Mar. 9, 2021**

CLAIM

We claim, the ornamental design for a confection, as shown and described.

DESCRIPTION

FIG. 1 is a top, right side perspective view of a confection showing our new design;

FIG. 2 is a top plan view thereof;

FIG. 3 is a bottom plan view thereof;

FIG. 4 is a right side elevation view thereof;

FIG. 5 is a left side elevation view thereof;

FIG. 6 is a front elevation view thereof; and,

FIG. 7 is a rear elevation view thereof.

The broken line disclosure forms no part of the claimed design.

The dash-dot-dash lines indicate boundary between the claimed shaded subject matter shown with shading and unclaimed subject matter shown without shading.
